BRAKE ADJUSTMENT

Gilbert K. House, Dayton, Ohio, assignor to General Motors Corporation, Detroit, Mich., a corporation of Delaware

Application August 14, 1935, Serial No. 36,100

2 Claims. (Cl. 188—79.5)

This invention relates to brakes and particularly to brakes for motor vehicles.

The object of the invention is to provide an improved means for adjusting the release position of the shoes of an internal brake.

Other objects and advantages will be understood from the following description.

In the accompanying drawing:

Fig. 1 is a vertical section through a brake drum showing my novel adjustment means for the shoes.

Fig. 2 is a section on line 2—2 of Fig. 1.

Fig. 3 is a perspective of a detail.

Fig. 4 is a plan view, partly in section, of a modified form.

Referring to the drawing, numeral 5 designates a brake drum to be carried by a vehicle wheel as usual. To fixed anchor plate 7 are pivoted at 9 articulating links 11 and 13. At 15 and 17 these links are pivoted to drum engaging shoes 19 and 21. The shoes have linings 23. To anchor plate 7 is secured by fastening means 25 a wheel cylinder 27 of a hydraulic brake system. Within the wheel cylinder are pistons 29 with packing 31. A spring 33 is located between the pistons to hold packing 31 against pistons 29, and suitable hydraulic medium from a conventional master cylinder enters at 35. Slidable within each end of the cylinder is a plunger 37 of cup shape, its head 39 engaging the similarly shaped head 41 of an outer cup 43 slidably engaging the wall of the cylinder 27. The two cups 43 engage the adjacent ends of the two shoes and spread them apart when the pistons are separated by the introduction of fluid medium through opening 35.

Adjustably mounted on the cover or fixed plate 7 is a stop device 45 shown best by Fig. 3. This device has a flat part 47 lying against the fixed plate 7. This flat part 47 has a bent up end 49, an elongated opening 51 and a tongue 53, the latter turned up from the material of the part 47 into parallelism with end 49. A substantially right angled part 54 is cut away to form an arc 57. Webs 59 unite the two parts. The dimensions are such that while part 47 lies against the fixed plate 7 the arcuate surface 57 will lie against the circumferential wall of the cylinder as shown by Fig. 2. The cup 43 may slide along the cylinder wall. When retracted, it engages the part or wall 54 adjacent the arcuate surface 57. The walls 54 of the two parts 45 serve, therefore, to limit the release position of the cups 43 and, therefore, of the brake shoes when drawn to their position of release by spring means 59, 61.

As the shoe lining 23 becomes worn it is necessary to adjust outwardly the stops 45 so that the cups 43 engage the stops in new positions of the latter axially of the cylinder. Through a circular hole in the plate 7 and through the elongated

opening 51 of the stop device is a pin 63 carrying an eccentric 65 located between the end 49 and tongue 53. As the pin is turned by using a suitable tool on its head 55, the eccentric rotates and pushes member 45 to provide a new stop position for the cups 43 and therefore for the brake shoes. Numeral 56 is a lock nut to hold the eccentric 65 in positions of adjustment.

Fig. 4 shows a modified form. In this form the pistons 67 are of inverted cup shape and are provided with packing 31. A spring 33 is used as before. The open ends of the cup-shaped pistons 67 engage the bottom walls of cups 69. To the bottom walls of each cup 69 is secured, as by riveting, a stem 71, bifurcated at 73, to engage the adjacent brake shoe 19 or 21.

To the inside open end of each cup 69 is threaded an angular member 75, one face of which carries screw threads and the other face of which engages a shoulder 77 formed on the cylinder 27. Teeth 79 on the member 75 are accessible by removal of a cover 81 from over an opening 83 in the fixed plate 7. The limiting inward position of the cups 69 and of the shoes is determined by the engagement of the angular part 75 with the shoulder. Adjustment of the cup 69 relative to member 75 changes the release position of the shoes.

In both forms the cylinder has been shown as having pistons hydraulically applied. It will be understood that cam means of any known type may be substituted as the instrumentality for spreading the pistons 29 or 67, in which case similar provision for adjustment may be employed.

I claim:

1. In combination, a drum, a cover plate, shoe means to frictionally engage said drum, reciprocable means to engage and move said shoe means, movable means adapted to engage and move said reciprocable means, and an adjustable member supported on said cover plate and adapted to be engaged by said reciprocable means to determine the release position of said shoe means, said adjustable member having opposed lugs, a disc between said lugs and a bolt eccentrically secured to said disc, and means to secure said bolt in positions of adjusted rotation to said cover plate.

2. In combination, a drum, a cover plate, shoe means within the drum, a wheel cylinder, a plunger therein, a cup reciprocable upon the end of the cylinder, engaged by the plunger and adapted to engage and move the shoe, an angular member having one face adjustably secured to the cover plate and its other face positioned to be engaged by the marginal edge of said cup to determine a release position of the shoe means.

GILBERT K. HOUSE.
